Primary Examiner — Leanne Was-Englehart*(74) Attorney, Agent, or Firm* — Taft Stettinius & Hollister LLP; Stephen F. Rost(57) **CLAIM**

The ornamental design for a clip for a door assembly of an animal enclosure, as shown and described.

DESCRIPTION

FIG. 1 is a perspective view of a clip for a door assembly of an animal enclosure shown in environmental use according to the present design;

FIG. 2 is a second perspective view thereof;

FIG. 3 is a front view thereof;

FIG. 4 is a bottom view thereof;

FIG. 5 is a top view thereof;

FIG. 6 is a right side view thereof;

FIG. 7 is a left side view thereof; and,

FIG. 8 is a rear view thereof.

The broken lines depict environment that forms no part of the claimed design.
